FIG.2

FIG.3

Des. 183,383

PAGE 3

Figure 1 is a perspective view of a hydroplane, showing my new design;

Figure 2 is a side elevational view;

Figure 3 is a front elevational view;

Figure 4 is a plan top view with a portion of one wing broken away for convenience of illustration;

Figure 5 is a fragmentary plan view of the bottom; and

Figure 6 is a rear elevational view.

The dominant features of the design reside in the portions shown in full lines.

I claim:

The ornamental design for a hydroplane, as shown and described.
